UNITED STATES PATENT OFFICE.

ORAN A. HONSINGER, OF TACOMA, WASHINGTON.

FOLDING BED.

1,035,911.

Specification of Letters Patent.

Patented Feb. 3, 1914.

Application filed February 29, 1913. Serial No. 750,532.

To all whom it may concern:

Be it known that I, ORAN A. HONSINGER, a citizen of the United States of America, and a resident of the city of Tacoma, in the county of Pierce and State of Washington, have invented certain new and useful Improvements in Folding Beds, of which the following is a specification.

My invention relates to beds capable of being folded and, if desired, converted into another form or piece of furniture, and has for one of its objects the provision of a construction of this character which is simple, capable of being easily set up or folded, and which, when in its last named position, affords ample space for the bedding.

With the above and other objects in view, to be referred to as my description progresses, my invention resides in the features of construction, arrangements and combinations of parts hereinafter described and succinctly defined in my annexed claims.

Referring to the accompanying drawing wherein like numerals of reference indicate like parts throughout: Figure 1 is a side elevation illustrating my invention in open position. Fig. 2 is a fragmentary top plan thereof with portions broken away. Fig. 3 is an elevation illustrating the bed folded, a portion of the main supporting frame or box being broken away, and Fig. 4 is a vertical cross section through one side portion of the bed, taken on line 4—4 of Fig. 1.

Referring to the drawing by numerals of reference, 1 and 2 indicate end sections, and 3 an intermediate section, the latter being hinged, as by pivots 20, to sections 1 and 2 and forming in conjunction therewith the bed frame across which the usual spring bottom, as 30, extends. Sections 1 and 3 are pivotally mounted on swinging supports, conveniently consisting of pairs of bar members 4 and 5, which are pivoted at 4', 5' respectively, to the opposite end portions of a main supporting frame 6, the pivots 4' being below the pivots 5', as clearly shown in Figs. 1 and 4. Support members 4 and 5, the former of which have their outer end portions offset both inwardly and rearwardly relatively to frame 6, are pivoted at 4", 5" to bed frame sections 1, 3 respectively,

and when the bed is open and the sections 1, 2 and 3 therefore disposed in a common plane, they preferably extend upwardly from main frame 6 in diverging relation. 55

Reference numeral 7 indicates connecting links for the support members 4, 5 the same being pivoted at 7' on widened portions thereof, whereby each pivotal point 7' will be similarly offset with respect to an imaginary line intersecting the adjacent pivots 5', 5". Support members 5 are provided with rigid extensions 5', which, with the bed open, project forwardly of and above pivots 5". Pivotedly connected, as at 8', with extension 5" are links 8, the same having their other end portion provided with slots 8" which freely receive studs 9 of bed frame section 2. Studs 9 engage the outer end walls of slots 8" when the bed is open to thereby prevent rearward tipping of the bed frame except when section 2 is swung upwardly. 65 70 75

Reference numerals 10 indicate legs pivoted at 11 and 12 to frame section 2 and adjusting bars 13 respectively, which latter are pivoted at 13' to bed frame section 3, whereby relative movement of one of the sections 2, 3 with respect to the other will effect opening and folding movements of 80 the legs. 85

Main frame 6, can be of any desired construction. As shown, it is rectangular in form, so as to inclose the folded bed frame, and provided with a hinged top wall or cover 16, whereby it can serve as a couch or seat, when the bed is folded therein.

To fold the bed, the operator swings section 2, the same swinging on section 3 until studs 9 engage the end walls of slots 8", when the movement of said section 2 will be communicated through links 7, 8 to support members 4, 5, causing the latter to swing downwardly into frame 6 to a relatively inverted position; during which movement, the support members swinging eccentrically to one another, the joint between sections 1, 3 breaks inwardly. The closed or folded position of the bed frame is reached when sections 1 and 2 come into parallel relation 95 with intermediate section 3 at substantially right angles thereto, see Fig. 3, at which 100

time studs 9 engage the inner end wall portions of slots 8', and tend to prevent further folding movement. Bed frame member 2 serves also in the capacity of a lever 5 to open the bed, the same being grasped and pulled upwardly and outwardly, as will be readily understood.

Pivots 5^a conveniently consist of end extensions of a strut 22, which extensions project through and beyond the side bars of frame section 3.

Having thus described my invention, what I claim as new, and desire to secure by Letters Patent of the United States of 15 America, is:—

1. In a bed structure of the character described, a bed bottom frame comprising an intermediate and two end sections hinged to the intermediate section, pivotally mounted 20 supports, one of which is pivoted to the intermediate frame section, the other being pivoted to one of the end sections and a link pivoted to the other end section, the first-named support projecting above said intermediate frame section when the bottom 25 frame is in open position, and said link being pivoted to said projecting portion.

2. In a bed structure of the character described, a bed bottom frame comprising an 30 intermediate section and end sections hinged thereto, supporting means for said frame comprising spaced swinging supports, one of which is pivotally connected to the intermediate section between its ends and the 35 other to one of the end sections, and a link connection between the first-named support and the other end section.

3. In a bed structure of the character described, a bed bottom frame comprising an 40 intermediate section and end sections hinged to the intermediate section, supporting means for said frame comprising spaced swinging supports, one of which is pivotally connected to the intermediate section 45 and the other to one of the end sections, a link connection between the other end section and the first named support, and a link connection between the supports.

4. In a bed structure of the character described, a bed bottom frame comprising an 50 intermediate section and end sections hinged thereto, swinging supports, one of which is pivotally connected to the intermediate section and the other to one of the end sections, means pivotally connecting the supports, and motion-transmitting means connecting the other end section to one of the supports.

5. In a bed structure of the character described, a bed bottom frame comprising an 60 intermediate section and end sections hinged thereto, swinging supports having pivotal connections respectively with the intermediate section and one of the end sections, a

stud on the other end section, and a link 65 pivoted to one of said supports and having a slot receiving said stud.

6. In a bed structure of the character described, a bed bottom frame comprising an intermediate section and end sections pivot- 70 ed thereto, swinging supports respectively connected to the intermediate section and one of the end sections, one of said supports having an extension projection above the frame when the latter is in open position, and a link pivoted to the projecting portion of said support and to the other end section.

7. In a bed structure of the character described, a bed bottom frame comprising an 80 intermediate section and end sections hinged thereto, swinging supports pivoted respectively to one of said end sections and the intermediate section, a link connection between one of said supports and the other 85 end section, the connection of the link with said support being spaced from the connection of the latter with the intermediate section, a leg pivoted to the last-named end section, and a link connection between the leg 90 and the intermediate section, said link connection constituting means for swinging the leg during the relative movement of the frame section.

8. A main supporting frame comprising a 95 casing having side and end walls, a pair of supports pivotally mounted on each end wall, one support of each pair being pivot- 100 ed at a point lower than the other, said supports having projecting portions, links piv- 105 ed to the projecting portions, a bed bottom frame comprising an intermediate section and end sections pivotally connected thereto, pivotal connections between the supports and the intermediate and one end section respectively, an extension carried by one of the supports and projecting above the frame when the latter is open, and a link pivoted to said extension and having a slotted connection with the other end section.

9. In a bed structure of the character described, the combination with a base, of spaced swinging supports pivotally mounted thereon, a bed bottom frame comprising an intermediate section and end sections 115 hinged thereto, a pivotal connection between one support and one end section, a pivotal connection between the other support and the intermediate section, and a link connected to the latter support at one side of its pivotal connection with the intermediate section, said link being connected to the other end section.

10. In a bed structure of the character described, the combination with a base, of 125 spaced swinging supports pivotally mounted thereon, a bed bottom frame comprising an intermediate section and end sections

hinged thereto, a pivotal connection between one support and one end section, a pivotal connection between the other support and the intermediate section, and a link
5 connected to the latter support and having a limited sliding connection with the other end section.

Signed at Tacoma, Washington this 17th day of February 1913.
